Primary Examiner — Dana K Weiland*Assistant Examiner* — Kathryn Elizabeth Zieno(74) *Attorney, Agent, or Firm* — QUARLES & BRADY LLP(57) **CLAIM**

The ornamental design for a coupling, as shown and described.

DESCRIPTION

FIG. 1 is an isometric view of a top, front, and right side of an ornamental design for a coupling;

FIG. 2 is a front elevational view of the coupling of FIG. 1; FIG. 3 is a rear elevational view of the coupling of FIG. 1; FIG. 4 is a right side elevational view of the coupling of FIG. 1;

FIG. 5 is a left side elevational view of the coupling of FIG. 1;

FIG. 6 is a top plan view of the coupling of FIG. 1; and, FIG. 7 is a bottom plan view of the coupling of FIG. 1. The dash-dash-dash lines illustrate portions of the coupling that form no part of the claimed design.

1 Claim, 7 Drawing Sheets(56)
